UNITED STATES PATENT OFFICE

132,662

DESIGN FOR A COMBINED SALT SHAKER, PEPPER SHAKER, AND TRAY THEREFOR

Samuel J. Carnes, Camden, Ark.

Application December 30, 1941, Serial No. 104,906

Term of patent 3½ years

To all whom it may concern:

Be it known that I, Samuel J. Carnes, a citizen of the United States, residing at Camden, in the county of Ouachita and State of Arkansas, have invented a new, original, and ornamental Design for a Combined Salt Shaker, Pepper Shaker, and Tray Therefor, of which the following is a specification, reference being had to the accompanying drawing, forming part thereof.

Fig. 1 is a top plan view of a combined salt

shaker, pepper shaker and tray therefor, showing my new design;

Fig. 2 is a side elevational view; and
Fig. 3 is a perspective view thereof.

I claim:

The ornamental design for a combined salt shaker, pepper shaker, and tray therefor, as shown.

SAMUEL J. CARNES.
